UNITED STATES PATENT OFFICE.

CHARLES D. McARTHUR, OF PITTSBURGH, PENNSYLVANIA, ASSIGNOR TO BLAW-KNOX COMPANY, OF PITTSBURGH, PENNSYLVANIA, A CORPORATION OF NEW JERSEY.

CONSTRUCTION OF CONCRETE POLES.

Application filed June 15, 1923. Serial No. 645,524.

My invention relates to the construction of concrete poles and the like.

Heretofore, concrete poles for telegraph and telephone lines, electric lighting circuits, etc., have been cast or molded at a central plant, then transported to the points of use, and there erected or "set" in holes dug for them in the usual manner—just about like wooden or steel poles. In order to have the "beam" strength to stand handling and shipping in this manner (for the most part on their sides), such concrete poles require more metal reinforcement than their ultimate service as poles would call for; and in order to be light enough for transportation and handling in the ordinary way, such poles must be fabricated with less concrete in their cross section than is really needed to protect their reinforcement adequately. At best, the handling, transportation and erection of the poles is a rather troublesome and costly matter.

I aim to overcome this and other drawbacks of present practice by constructing and setting concrete poles *in situ*, so as to do away with the necessity for transporting and handling the poles. In this way, it becomes practicable to put into the poles enough concrete to protect their reinforcement effectually, and thus make them last longer, while at the same time economizing on the reinforcement itself. My invention also allows the labor cost of a pole line to be reduced, by constructing or fabricating the poles ready "set" tight and firm in their holes.

Various other advantages obtainable through my invention will appear from my description hereinafter of the best methods and apparatus for the purpose that are known to me.

In the drawings, Fig. 1 is an elevation illustrating the molding of a pole upright in its hole in accordance with my invention, by means of a novel apparatus or machine which I have devised for the purpose.

Fig. 2 is an elevation of the machine alone from the left of Fig. 1, with various parts in section as indicated by the line 2—2 in that figure.

Fig. 3 is a fragmentary plan view of parts at the top of the machine, on a larger scale than Figs. 1 and 2.

Fig. 4 shows a fragmentary sectional view through the upper portion of the machine on a still larger scale, taken as indicated by the line 4—4 in Fig. 1.

Fig. 5 is a side elevation of the apparatus collapsed (so to speak) for hauling to or from the job or field of use.

Fig. 1 shows a hollow pole mold form 10 set more or less upright over a hole H, so that form and hole together afford one continuous mold. As shown, the hole H is without lining of any sort. The metal rods 65 or other reinforcements h for the pole are appropriately held in place in the form, and extend from above the ground down into the hole H. As shown, indeed, they extend from one end of the mold cavity to the other: i. e., from the top of the form 10 to the earth bottom of the hole H. When the concrete is poured, it fills the mold cavity and embeds the reinforcement h.

By thus forming the pole erect with the hole H as part of the mold, all necessity for filling in and tamping down earth in the hole around the pole is obviated; and the pole is at once "set" more solidly and firmly in the ground than it could be by tamping, even when skillfully done, which is often not the case. Only a hole of minimum standard size is required, and it need not (in many cases) be dug quite so deep, if the ground is firm.

As shown, the form 10 is divided longitudinally into half-round sections with flanges 12 detachably bolted together, so that the form can readily be removed from the pole molded therein as soon as the concrete has set sufficiently,—say in about 24 hours after pouring. For convenience in manufacture and shipment, the form 10 is similarly sectionalized transversely, as indicated by the flange joints 13 in each longitudinal half. As a means of compensating for oversize or other possible irregularities of pole holes, a cover plate 14 (apertured in correspondence with the internal cavity of the form 10) may be interposed between the form 10 and the earth around the hole H, for the form to stand on. Like the form 10 itself, the cover 14 may be divided for convenience in removal; and its halves may be bolted to the lowermost flanges 13 of the corresponding form halves.

100
105

In order to assure that the mold cavity shall be solidly and uniformly filled, it is preferable to fill it from the bottom upward and to deliver the concrete always at the continually rising bottom of the decreasing mold cavity, with some little force or pressure. As shown, the concrete is supplied under pressure from a pneumatic mixture 15, through a conduit 16 whose discharge end or nozzle 17 can be lowered through the open upper end of the form 10 to the initial earth bottom of the mold cavity, and then progressively drawn upward as the mold is filled. For this purpose, a mast or tower structure 20 may be provided, for supporting the conduit 16. These and their accessories, including an internal combustion engine or other enclosed power plant 21, are mounted on a wheeled vehicle or truck 22, so that they can be conveniently moved along from pole hole to pole hole, and hauled from one job to another. While a mold is being filled, the form 10 may be braced and held upright from the tower 20, by means of braces 23 bolted to the tower structure and to the mold flanges 13.

For serving the mixture 15 with cement and mineral aggregate (such as sand and broken stone), there is a conveyor or skip-bucket hoist 24 whose inclined ways 25 are pivoted at one end to bracket plates on a double triangular frame structure 26 at whose apices are the pulleys 27 for the bucket hoisting cables 28. In operation, these cables 28 are wound on or unwound from a drum 30 mounted on the frame 26, and reversibly driven from the power plant 21 through belting 31. When the ways 25 are in service, lateral lugs 32 about at their middle rest in the notched ends of brackets 33 projecting from the front of the vehicle 22; at other times, they may be swung up out of the way, to afford access to the pull member 34 attached to the front axle of the vehicle. When the skip bucket 24 is drawn up the ways 25 by the cables 28, its front strikes and raises the lid 35 of a charging opening in the mixer cover 36; also, its front wheels or rollers 37 are arrested by stops 38 on the ways 25, causing it to tilt (about as shown in dotted lines in Fig. 1) and dump its contents into the mixer. Compressed air to operate the mixer 15 and feed or force the mixed concrete through the conduit 16 is supplied from a compressor forming part of the power plant 21, through piping 39.

As shown in Fig. 1, a portion 16' of the conduit 16 associated with the tower 20 is flexible, and extends in a height over a supporting guide 40 through which it can be payed out or taken up to lower it into or draw it out of the form 10. The provisions shown for thus paying out or taking up the conduit 16' will be described hereinafter.

The guide 40 comprises a number of grooved-edged sheaves 41 whose mounting is carried by a supporting arm 42 clampably pivoted at 43 to a bracket at the top of a vertically adjustable "topmast" member or structure 44 that telescopes with the main structure of the tower 20. As shown in Figs. 1, 2 and 3, this structure 44 is of forked configuration, consisting of vertical channels 45 interconnected by horizontal members 46 and sliding between and against guide parts 47 and 48, with a standard composed of channels 49 back to back connected to its members 46 and carrying the pivoted support arm 42. The vertical adjustment of the support 42 takes care of differences in the lengths of the forms 10 used on different jobs, while its horizontal movement allows the machine to fill a form to one side of it, instead of in front of it as in Fig. 1.

As here shown, the supply conduit 16 extends from the discharge outlet of the mixer 15 along beneath the vehicle platform, then up within the truss-built tower frame 20 to an elevated point, and then bends down at 50, being held in place by supporting brackets 51 at suitable intervals. The flexible delivery portion 16 is connected to the portion 16 at 50, extends downward therefrom some distance within the tower 20, and then bends upward around the sheave of a pulley-block 52 and extends to the guide means 40—where it bends downward once more into position for lowering into the form 10, or vice-versa, as already explained. It will be seen, therefore, that by shifting the block 52 up or down, the flexible conduit 16' will be paid out or taken up. As here shown, provision is made for doing this by means of a cable 53, which is attached to the lower end of the block 52, extends down and around pulleys 55, then up and makes a number of turns around a drum 56, and finally on up over pulleys 57, and down to an attachment to the block 52 again. The drum 56 can be revolved either way, to raise or lower the pulley block 52. As shown, it is reversibly driven from the power plant 21 by a belt 58. The forked construction of the supporting means at 45, 45 affords free space within the tower 20 for the block 52 to move up and down without interference.

For convenience in hauling, provision is preferably made for lowering the tower or mast 20 and reerecting it at will. In the present instance, this is accomplished by a folding or tilting action, rather than by a collapsing one. For this purpose, the main portion of the tower 20 is pivoted to a base portion 60 (more permanently and fixedly attached to the vehicle chassis or platform) concentrically with the rotary drum 58 of the mechanism for paying out and taking up the conduit 16'. As shown in Figs. 1, 2 and 5, the shaft or spindles 61 of this drum

58 hinge together plates 62, 63 at the lower and upper forward corners of the truss-built tower 20 and base 60. A cable or rope 64 attached at one end to a downward extension 5 65 of the tower 20 (that carries the pulleys 55) extends to a drum 66, mounted on the vehicle chassis and provided with a crank for manual operation; by winding or un-winding this cable 64, the tower 20 can be 10 raised to the vertical position of Fig. 1 or lowered, ultimately, to the substantially horizontal position of Fig. 5. When raised, the tower 20 can be securely locked by means of a latch device 67 (Figs. 1 and 2). As shown, 15 the metal supply pipe or conduit 16 for the concrete is made in separate sections with a suitable self-tightening joint at 68 to permit this movement. When the tower 20 is lowered, its forward uprights engage and 20 rest on lugs or seats 69 at either side of the conveyor frame 26, and it is thus sustained and held against either vertical movement or lateral shifting or distortion. When the tower 20 is thus lowered, the skip ways 25 25 may be hooked up to it, as already mentioned, by the hook-ended link means 70. At such times, the pivot of the conduit support 42 can be clamped tight at 43 to hold it out of the way.

30 What I claim is:

1. Apparatus for constructing and setting a concrete pole in situ comprising an apertured cover for a pole hole, a longitudinally divisible sectional form adapted to stand upright on said cover, and a concrete delivery conduit with means for lowering the same through said form to the bottom of the hole and progressively drawing it upward as the mold cavity of hole and form is progressively filled from it.

2. Apparatus for constructing and setting a concrete pole in situ comprising a hollow form for cooperation with a pole hole, a concrete delivery conduit, and a movable tower with means for holding the form upright over the pole hole and means for lowering and drawing up the conduit through the form.

3. Apparatus of the character described comprising a vehicle with a tower and means for sustaining a pole mold form upright therefrom, a concrete mixer on said vehicle, and means carried by said tower for feeding concrete from said mixer into such form shiftable up and down, and in and out of the form.

4. Apparatus of the character described comprising a movably mounted tower and means for sustaining a pole mold form upright therefrom, a concrete delivery conduit, and means carried by said tower for lowering and drawing up the conduit through the mold cavity.

5. Apparatus of the character described comprising a vehicle with a tower and means

for sustaining a mold form upright therefrom, a concrete delivery conduit carried by said tower for insertion downward into the form to fill it, and a pneumatic mixer carried by the vehicle for forcing concrete through said conduit into the mold.

6. Apparatus of the character described comprising a movably mounted tower, a flexible concrete delivery conduit, means on said tower for supporting and guiding said conduit in a bight, to permit it to be lowered or drawn up through a mold, and means also carried by the movable structure for paying out and taking up said conduit.

7. Apparatus of the character described comprising a movably mounted tower, a concrete supply conduit extending to an elevated point on said tower, guide means at an elevated point on said tower, a flexible conduit connected to said supply conduit extending downward and then bending upward and over said guide means, and means engaging the upward bend of said flexible conduit movable up and down to pay out the conduit or take it up.

8. Apparatus of the character described comprising a movably mounted tower, a concrete supply conduit extending to an elevated point on said tower, a forked support telescoping with said tower and carrying overhanging guide means, a flexible conduit connected to said supply conduit extending downward and then bending upward and over said guide means, and means engaging the upward bend of said flexible conduit movable up and down, in the free space within the tower afforded by the forked construction of said support, to pay out the conduit or take it up.

9. Apparatus of the character described comprising a vehicle, an erectable tower and a concrete mixer carried by said vehicle, means on the vehicle for elevating and lowering said tower, a flexible conduit for delivering the mixed concrete from said tower, when elevated, to a pole form, and means for paying out or taking up said conduit.

10. Apparatus of the character described comprising a vehicle, a concrete mixer and a base structure on said vehicle, a folding tower on said base, a flexible conduit for delivering the mixed concrete from said tower to an upright pole form, with guide means for said conduit carried by said tower, and means for paying out or taking up said conduit including a rotary element concentric with the folding movement of said tower.

11. Apparatus of the character described comprising a vehicle with a concrete mixer thereon, a tower on said vehicle foldable lengthwise thereof down over the same, with means for delivering the mixed concrete from said tower, when elevated, to an upright pole form, and conveyor means for

serving the mixer including a frame structure engaging and sustaining the tower when lowered.

12. Apparatus of the character described comprising a vehicle with a concrete mixer and a folding tower thereon, a vertically adjustable and horizontally swingable support carried by said tower, a flexible con-

duit for delivering the mixed concrete to a pole form, and means carried by said support for guiding and sustaining said conduit in a bight, to permit it to be lowered or drawn up in a mold. 10

In testimony whereof, I have hereunto signed my name.

CHARLES D. McARTHUR.
